UNITED STATES PATENT OFFICE.

CHARLES W. SCOTT, OF MINNEAPOLIS, MINNESOTA.

DESIGN FOR A SAVINGS BANK.

Application filed May 11, 1927. Serial No. 21,931. Term of patent 14 years.

To all whom it may concern:

Be it known that I, CHARLES W. SCOTT, a citizen of the United States, residing at Minneapolis, in the county of Hennepin and State of Minnesota, have invented a new, original, and ornamental Design for Savings Bank, of which the following is a specification, reference being had to the accompanying drawings, forming part thereof, wherein:

Fig. 1 is a front elevation of a savings bank showing my new design.

Fig. 2 is a rear elevation of the same.

I claim:

The ornamental design for savings bank, as shown.

CHARLES W. SCOTT.
